Atty.

UNITED STATES PATENT OFFICE.

JOHN W. KUHRT, OF TOLEDO, OHIO.

DOORSTOP.

Application filed February 14, 1923. Serial No. 619,021.

To all whom it may concern:

Be it known that I, JOHN W. KUHRT, a citizen of the United States, and a resident of Toledo, in the county of Lucas and State of Ohio, have made an Invention Appertaining to a Doorstop, which invention is fully set forth in the following specification.

This invention relates to door stops and catches, and has for its object the provision of a simple, efficient and durable device of this character, which may be used either as a stop or buffer to limit the opening movements of a door, or as a catch to hold a door in releasable open position, the catch means being moved to operable door engaging position by a movement imparted to the stop or buffer means by a door when striking the same.

The invention is fully described in the following specification, and while, in its broader aspect, it is capable of embodiment in numerous forms, two embodiments only thereof are illustrated in the accompanying drawings, in which,—

Figure 1 is a vertical central longitudinal section of a device embodying the invention adapted particularly for indoor use, such device being mounted in operative position and in the act of being swung to catch position by the engagement of a door therewith. Fig. 2 is a similar view of the device, partly in full, with the catch means thrown to door engaging position. Fig. 3 is a fragmentary view similar to Fig. 1 and partly in full, with the door stop locked against catch operating movements. Fig. 4 is a side elevation of a different form of the device adapted particularly for outside work with a door in the act of striking the stop member and moving the catch member to operative position, the parts in which the device is mounted being fragmentarily shown and in section. Fig. 5 is a rear elevation of the device. Fig. 6 is a sectional view thereof on the line 6—6 in Fig. 5, with parts in full and with the catch means in door engaging position, and Fig. 7 is a fragmentary view similar to Fig. 6 with the stop means locked against catch operating movements.

Referring particularly to Figs. 1, 2 and 3 of the drawings, 1 designates a base plate which is adapted to be set into a recess 2 provided in a floor or other supporting means 3 in position for the lower edge of

a door 4 to swing over the same when moved to open position. A post or upright member 5 rises from the base plate 1 near the limit of desired opening movements of the door 4 and is provided in its top portion with a cross opening 6 and in its lower portion with a vertically disposed opening 7 which extends from the opening 6 down through the plate 1 and into the recess 2. A bell crank lever member 8 is fulcrumed at its elbow within the lower end portion of the post opening 7, as at 9, and has one arm extending up through said opening and into the cross opening 6 and its other arm extending lengthwise of the plate 1 beneath the same and in operating engagement with a catch plunger or stud 10, which is mounted for vertical reciprocatory movements in the plate 1 in spaced relation to the post 5.

A buffer or stop member 11, preferably of rubber or other yielding material, is carried by the upper end of the upright arm of the lever 8 for movements into and out of the cross opening 6 when the lever is rocked, the buffer member being disposed at the side of the lever adjacent to the catch plunger 10. When the upwardly projecting arm of the lever 8 is in its forwardly rocked position, as shown in Fig. 1, the buffer 11 projects a distance without the forward end of the opening 6 in position to be engaged and moved a distance into the opening 6 by the associated door 4 striking thereagainst, thereby effecting a rocking of the lever 8. The buffer 11, in the present instance, is mounted on the forwardly projecting end of the upright arm of the lever 8 and preferably has a spherical body portion *a* which fits into the opening 6 and has a flanged outer end portion *b*, which, when the buffer is forced into the opening 6, coacts with the outer marginal edge wall of such opening to stop the further movement of the buffer therein.

When the buffer 11 is in its forwardly projecting position, as shown in Fig. 1, the catch plunger 10 with which the opposite end of the lever 8 is connected, is in lowered inoperative position to permit the door 4 to freely swing across the same. The inward movement of the buffer occasioned by the door striking the same causes an upward movement of the catch plunger 12 in advance of the lower edge of the door 4 to hold the door in open position until the plunger has been depressed to its inoperative

position. Such depression of the plunger may be effected by stepping on the same. It is preferable to make the plunger 10 longitudinally adjustable as to length to suit the distance between the lower edge of the door 4 and base plate 1, and for this purpose a plug 12 is adjustably threaded in the other end of the plunger.

A lock member 13 of lever form is pivoted 10 in the rear end portion of the opening 6 and is adapted to be disposed in released relation to the lever 8, as shown in Fig. 1, or to be thrown into locking engagement with the upper end portion of such lever, as shown in Fig. 3, to prevent an inward rocking of the buffer 11 and a consequent upward movement of the catch plunger 10 into door holding position when a door strikes the buffer. It is thus evident that when 20 the lock member 13 is in locking engagement with the lever 8 the device acts solely as a buffer member for the door.

The form of the invention shown in Figs. 4 to 7 is adapted more particularly for outside or heavy work, for instance, for use in connection with garage doors. In this form the base plate is eliminated and the post 15, which carries the buffer and catch lever, is made somewhat larger and heavier than the 30 post 5 of the other form, and may be screwed at its lower end into a pipe 16 set in concrete 17. The buffer and catch lever 18 is considerably heavier than that of the other form and is disposed above the concrete 35 flooring or driveway 17, being pivoted at its elbow portion within the post 15 at 19. The upwardly projecting end portion of the lever, which is disposed within a hollow portion of the post, has the buffer 20 secured 40 to and projecting forwardly from its upper end through a side opening in the post. The opposite end of the lever is provided with an upturned stud or catch portion 21, which, when the lever is thrust to operative catch 45 position, is disposed in advance of the lower edge of the associated open door 22, as shown in Fig. 6. The lever 18 is locked in inoperative catch position by the engagement of a locking finger 23 therewith, as 50 shown in Fig. 7, such finger being rockable into released position.

I wish it understood that my invention is not limited to any specific construction, arrangement or form of the parts, as it is capable of numerous modifications and changes without departing from the spirit of the claims.

What I claim as new and desire to secure by Letters Patent, is,

1. The combination with a door and a stationary part over which the door swings, of a post rising from said part in the path of opening swinging movement of the door, a bell crank lever member fulcrumed adjacent to the base portion of the post and

having an arm projecting upwardly through the post and carrying a door buffer in exposed position in the path of movement of the door whereby it is moved to rock the lever by the striking of the door thereagainst, and means at the forward end of the other lever arm operated by a door actuated movement of the lever to move into catch engagement with the door.

2. The combination with a door and a stationary part over which the door swings, of a member rigidly rising from said part and having a vertical opening therein with a cross opening at its upper end, a lever pivoted for vertical rocking movements with an arm projecting up into the vertical opening of said member and having a buffer at its upper end projecting out through the cross openings in the path of movement of the door whereby the lever is rocked by the door, and means at the opposite end of the lever for moving into catch engagement with the forward side of the door when the lever is rocked by the door.

3. The combination with a door and a stationary part over which the door swings, of a bell crank lever pivoted for vertical rocking movements relative to said part and having one arm projecting upward and provided with a buffer portion projecting in the path of movement of the door whereby a rocking of the lever is effected by a striking of the door against the buffer, and means at the opposite end of the lever movable relative thereto and operable by a door actuated rocking movement of the lever to move into catch engagement with the door to hold it in open position.

4. The combination with a door and a stationary part over which the door swings, of a bell crank lever pivoted for vertical rocking movements relative to said part and having one arm projecting upward and provided with a buffer portion projecting in the path of movement of the door whereby a rocking of the lever is effected by a striking of the door against the buffer, means at the opposite end of the lever operable by a door actuated rocking movement of the lever to move into catch engagement with the door to hold it in open position, and means operable to lock the lever against door actuated movements.

5. The combination with a door and a stationary part over which the door swings, of a member rigidly rising from said part and having a vertical opening therein with a cross opening at its upper end, a lever pivoted for vertical rocking movements with an arm projecting up into the vertical opening of said member and having a buffer at its upper end projecting out through the cross openings in the path of movement of the door whereby the lever is rocked by the door, means at the opposite end of the lever

for moving into catch engagement with the forward side of the door when the lever is rocked by the door, and means carried by said member and operable to releasably lock the lever against door actuating movements.

6. The combination with a door and a stationary part over which the door swings, of a member rising from said part in the path of movement of the door and having an opening therein, a bell crank lever pivoted for vertical rocking movements relative to said part and having a part projecting into said member and a part projecting under the door when in open position, a door buffer carried by the part of the lever projecting into said member and movable into the opening of the member and adapted to have stop engagement with a portion of the member to limit the door actuating movements of the buffer and the consequent rocking movements of the lever, and means at the opposite end of the lever movable into catch engagement with the door to hold it in open position when the lever is moved by the door.

7. The combination with a door and a stationary part over which the door swings, of a bell crank lever mounted for vertical rocking movements relative to said part and having one arm provided with a buffer portion disposed in the path of movement of the door whereby a rocking of the lever is effected by a striking of the door against the buffer, and a catch member mounted in the stationary part for movements into and out of the path of movement of the door, said lever having loose connection with the catch member to impart an upward movement to the member when the lever is rocked by the door.

8. The combination with a door and a stationary part over which the door swings, of a catch member mounted in the stationary part for vertical reciprocating movements

into and out of the path of movement of the door, a lever mounted for rocking movements relative to said stationary part and having a portion disposed in the path of movement of the door whereby movement is imparted to the lever by the door and having another part connected to said member to move the same into operative catch relation to the door when the lever is rocked by the door.

9. The combination with a door and a stationary part over which the door swings, of a catch member mounted in the stationary part for vertical reciprocating movements into and out of the path of movement of the door, said member being longitudinally adjustable, a lever mounted for vertical rocking movements relative to said stationary part and having a portion disposed in the path of movement of the door whereby movement is imparted to the lever by the door and having another part connected to said member to move the same into operative catch relation to the door when the lever is rocked by the door.

10. The combination with a door and a stationary part over which the door swings, of a catch member mounted in the stationary part for vertical reciprocating movements into and out of the path of movement of the door, a lever mounted for vertical rocking movements relative to said stationary part and having a portion disposed in the path of movement of the door whereby movement is imparted to the lever by the door and having another part connected to said member to move the same into operative catch relation to the door when the lever is rocked by the door.

In testimony whereof I have hereunto signed my name to this specification.

JOHN W. KUHRT.
